UNITED STATES PATENT OFFICE.

THOMAS WILLIAM STAINER HUTCHINS, OF DAVENHAM, ENGLAND.

APPARATUS FOR THE DISTILLATION OF CARBONACEOUS MATERIALS.

Application filed November 2, 1921. Serial No. 512,319.

To all whom it may concern:

Be it known that I, THOMAS WILLIAM STAINER HUTCHINS, a subject of the King of Great Britain and Ireland, and resident of Davenham, in the county of Cheshire, England, have invented certain new and useful Improvements in Apparatus for the Distillation of Carbonaceous Materials, of which the following is a specification.

10 This invention relates to apparatus for the distillation of coal, oil shale, and other like materials, and more particularly to apparatus of the rotary tube type which is externally heated to effect the low temperature distillation of the coal, oil shale or like material passing therethrough.

The object of the invention is to provide improved and efficient means for preventing the caking within the retort of the material being distilled therein, and/or the adhesion of the said material or of the distillate volatile matter to the walls of the retort which would prevent or interfere with the flow of the material through the retort and/or reduce the heat efficiency of the latter and its internal temperature.

My invention comprises the combination with an externally heated rotatable horizontal or inclined tube in which distillation 30 of the material is effected, of one or more tumblers which may extend from end to end or through any desired portion of the length of the tube, each tumbler comprising radial arms upon which the tumbler can 35 rest, each tumbler being adapted to be carried round the inner surface of the tube as the latter rotates until it overbalances, falls by its own weight, and strikes the tube with such force as to cause a yielding movement and/or act as a hammer 40 which results in the freeing of any material caked upon the tube and the breaking up of any caked material within the tube.

45 My invention further comprises the details of arrangement of the improved apparatus hereinafter described and claimed.

Referring to the two accompanying sheets of explanatory drawings:—

50 Figure 1 is a longitudinal sectional elevation of a distillation retort constructed and arranged in one convenient form in accordance with my invention.

Figure 2 is a sectional end elevation on the line AB of Figure 1.

Figures 3 and 4 are respectively sectional elevation and end elevation of a jointing arrangement of the revolving tubular retort.

The same reference letters in the different views indicate the same parts.

The coal or like distillation plant comprises a rotating tube *a* which is adapted to be heated externally by hot gases passing through the chamber *b* on their way to the waste gas chimney *c*. The tube *a* runs on rollers *d* and is rotated by worm and worm wheel or other gearing at *e* as shown.

Within the tube *a* is mounted a tube *f* carried at one end by the blank flange plate *g* and carried at the other end by a spider or supports *h* from the tube *a*. A scoop *i* attached to the tube *f* is adapted to feed the coal or other material supplied through the hopper *j* to the trough *k*, into the tube *f*. This scooping up of the material against the weight of the material in the receptacle below the hopper will evidently cause a head of pressure on the material in the tube *f* and cause it to move gradually through the tube *f*.

The tube *f* contains a tumbler *m* which is adapted as the said tube rotates along with the tube *a*, to be carried round the inner surface of the tube for a short distance until it overbalances, when it falls by its own weight and strikes the tube with sufficient force so that it yields or vibrates momentarily and frees itself of any material which may tend to cake thereon. This effect is obtained by making the tumbler with radiating arms as illustrated. In Figure 2, the tumbler is shown over-balancing and commencing to fall. The tumbler also acts as a hammer and breaks up any caked material within the tube. There is also a scraping action between the tube *f* and the tumbler as the latter is carried partially round the tube and also when the tumbler strikes the tube on falling to the bottom thereof and this combined with the effect of the blow received by the tube on the impact of the falling tumbler thereon, effectually maintains the surface of the tube free from all adhering material.

To obtain this operation it is apparent that the material must be made to pass through the tube *f* at such a rate of speed that it will not accumulate therein to such an extent that the tumbler 105

will be prevented from striking and slightly rubbing the interior of the tube as described above. It is also apparent that the speed with which the material may be made to 5 pass through the tube *f* may be further regulated by changing the inclination of the tube *f* or increasing the head of pressure under the hopper *j* as well as by frequently withdrawing the material from the end of 10 the tube *f* opposite the hopper.

The coal or the like fed into the tube by the scoop *i* travels gradually towards the closed end *g* of the tube *f*. Adjacent such end the tube is perforated as shown at *n*, 15 Figure 1, so that the coal passes into the outer tube *a* and travels there along towards the hopper *o* from which the residue can be withdrawn at intervals through the door *p*.

The material entering the tube *f* is 20 subjected to the lowest temperature as the heat is obtained through the annular space between the two tubes. This facilitates the distillation of the lighter oils which issue together with the gases distilled from the material, into the chamber *o* and pass to the gas off-take *q*.

By reason of the closure of the inner and outer tubes at *g*, the heating of the part of the tube *a* at which the gearing *e* is situated is obviated and heat losses due to radiation minimized.

I may, if desired, provide small tumblers as *m* in the space between the two tubes *a* and *f* but this may be unnecessary as the 35 material which passes from the tube *f* to the tube *a* through the perforations *n* may not have caking properties due to the partial distillation of its volatile constituents.

The distillates produced in the annular 40 space between the two tubes pass into the chamber *o* where they mix and pass away with the distillates from the tube *f*.

In practice, it is found that the tube *a* may not remain truly cylindrical but may 45 buckle slightly and further end play must be allowed for during working. To allow of such end play and to obviate a rigid joint between the tube *a* and the chamber *o* whilst providing a gas tight connection 50 there, I may employ the flexible diaphragm joint shown in Figures 3 and 4. In this, there is a collar or ring *s* secured upon and rotating with the retort or tube *a*. The diaphragm *t* carries a jointing ring *u* which is 55 held against the end face of the collar *s* by a series of tension springs *v*. With this construction, a gas tight joint is continuously maintained between the tube *a* and the chamber *o* by the jointing ring *u* and collar 60 *s*, notwithstanding any end movement of the tube *a* or twisting of the same.

I do not limit myself to the employment 65 of two tubes as *a* and *f* but may employ one tube as *a* having a tumbler therein, receiving the coal or other material at one end

and discharging the residue at the other end, but the arrangement of two tubes enables me to place the gas off-take, the coal feed and the ash discharging means at one end of the retort so that one gas tight joint 70 only around the tube *a* is necessary.

I claim:

1. An apparatus for distilling coal, oil shale and the like including a substantially horizontal rotatable retort tube adapted to receive the material to be distilled, means for producing a head of pressure on the material at one end of said tube a tumbler arranged in said tube extending parallel to the axis of said tube and having spaced arms extending outwardly from its longitudinal axis the spaces between the arms being open from end to end of the tumbler, said tumbler being of such size and weight as to move with the inner surface of the retort tube until the portion of the surface which the tumbler engages has moved upwardly to a predetermined extent, and at this time to tumble over and strike said surface with sufficient force to loosen any material tending to adhere to said inner surface. 85

2. A distilling apparatus as claimed in claim 1 in which said tumbler extends substantially the entire length of said tube. 90

3. A distilling apparatus as claimed in claim 1 in which said tumbler extends substantially the entire length of said tube and is at any part thereof of substantially star-shaped cross-section. 100

4. A distilling apparatus including a rotatable tube adapted to receive at one end the material to be distilled, an outer tube surrounding the first mentioned tube and movable therewith, a closure for both tubes located some distance within the end of the outer tube, ports arranged near the end of the inner tube for permitting communication between the interiors of the tubes, and outlet ports arranged at the opposite end of the outer tube for permitting the products of distillation to escape from the interior of the tubes. 105

5. A distilling apparatus including a rotatable tube adapted to receive at one end the material to be distilled, an outer tube surrounding the first mentioned tube and movable therewith, a closure for both tubes, ports arranged near the end of the inner tube for permitting communication between the interiors of the tubes, and outlet ports arranged at the opposite end of the outer tube for permitting the products of distillation to escape from the interior of the tubes, and a casing for both the inlet end 115 of the inner tube and the outlet end of the outer tube. 120

6. A distilling apparatus including a rotatable tube adapted to receive the material to be distilled, a casing surrounding the end 130

of the tube, means for closing the space between the tube and casing including a flexible diaphragm connected to the casing, a ring fixed to the tube, and resilient means for maintaining said ring in engagement with the diaphragm.

7. A distilling apparatus including an outer rotatable retort tube, an inner retort tube arranged in the outer tube, means arranged near one end of the inner tube for placing the interiors of the tubes in communication, means for feeding the material to be distilled into the other end of the inner tube, means for discharging the products of distillation from the outer tube, means for rotating said tubes, and a tumbler extending substantially the entire length of the inner tube and arranged within the latter, said tumbler being provided with outwardly extending supporting arms adapted to strike said inner tube for preventing the accumulation of carbon and the like on the inner surface of the same.

8. The process of distilling coal, bituminous shale or like materials which consists in feeding it into one end of a substantially horizontal tube, under a head of pressure, pulverizing the material and simultaneously keeping it moving through the tube by intermittently jarring the tube and scraping the inner surface of the tube to prevent adherence of the material to its interior surface, and simultaneously applying heat to the tube so as to gradually heat the material

as it passes from one end to the other of the tube.

9. The process of treating material which consists in feeding it into one end of a substantially horizontal tube, pulverizing the material and simultaneously keeping it moving through the tube by intermittently jarring the tube and scraping the inner surface of the tube to prevent adherence of the material to its interior surface.

10. In combination, a substantially horizontal rotatable tube, a tumbler arranged in said tube and having spaced blades extending outwardly from its longitudinal axis, and means for feeding material to be treated into one end of said tube, the opposite end of the tube having an outlet opening always substantially on a level with the bottom of the tube to permit the free discharge of material from the tube and thus prevent the accumulation of material within the tube, said tumbler being of such size and weight as to move within a surface of the tube until the portion of the surface which the tumbler engages begins to move upwardly, causing the tumbler at this time to tumble over and strike said surface with a scraping action and with sufficient force to loosen any material tending to adhere to said inner surface.

In testimony whereof I have signed my name to this specification.

THOMAS WILLIAM STAINER HUTCHINS.
